UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

COMBINED ROUNDING AND CHANNELING MACHINE.

1,099,334.

Specification of Letters Patent.

Patented June 9, 1914.

Application filed January 11, 1905. Serial No. 240,532.

To all whom it may concern:

Be it known that I, HARRIE A. BALLARD, of Ashland, in the county of Middlesex and State of Massachusetts, have invented certain new and useful Improvements in Combined Rounding and Channeling Machines, of which the following is a specification.

This invention relates to that class of shoe machines known as "rough rounders," which are employed after the outersole has been attached to a shoe, but before it has been sewed thereto, to trim the surplus leather from the edge of the sole and to cut a channel in the newly-outlined sole to receive the stitches of the final sewing operation.

The principal features of the invention are a novel work-feeding mechanism and a novel sole-rounding knife which coöperate in producing an extremely efficient combination of devices for the purpose.

The sole-trimming knife in the present invention is chisel-shaped and in addition to a chisel-like motion it receives a lateral edge-wise motion. These two motions combined cause the knife to describe a substantially circular bodily slicing motion. The knife is so timed that it moves with and operates on the work during the feeding thereof.

For the purpose of feeding the work, I employ a pair of coacting surface-engaging jaws which are caused to open and close by the action of the rounding-knife, and which receive a positive feeding motion from another source. Both of said jaws are carried by one and the same member, hence a simultaneous feeding movement of both is insured. One of said jaws is adapted to co-operate with the knife by resisting the pressure thereof during the cutting of the sole. The jaw therefore constitutes a cutting-block, but unlike the majority of cutting blocks which have a surface of suitable material against which the knife is forced, the jaw is cut away so that the cutting edge of the knife may project beyond the plane where the jaw resists the work. This feature insures a smoother, cleaner cut than heretofore, and obviates much wear on the knife.

Another feature of the invention is a work-guide or gage which may be manually moved during the operation of the machine to vary the width of the sole extension left

by the rounding-knife. Heretofore, in rounding a sole which is trimmed close at the shank, and which has a wide extension around the forepart, it has been necessary to employ two gages for the purpose.

Other features of the invention are illustrated on the drawings, described in the following specification, and pointed out in the claims.

Of the accompanying drawings:—Fig. 1 is a right side elevation of a "rough-rounding" constructed in accordance with the present invention. Fig. 2 is a front elevation of the same. Fig. 3 is a top plan view of the forward feeding jaw and actuating mechanism in closed position, as shown by Fig. 1 in side elevation. Fig. 4 is a section on the line 4—4 of Fig. 1. Fig. 5 shows the same parts in open position. Fig. 6 shows in elevation the feeding and trimming devices in open position. Fig. 7 is a left side elevation of a portion of the head and controlling levers. Fig. 8 is a front elevation of each of the work-feeding jaws.

On the drawings, the same reference characters indicate the same parts, wherever they occur.

Referring first to Fig. 1, the various operative elements are combined in a head 10, suitably mounted upon a standard 11, of which only the upper end appears. A clamping stud 12 upon which the head is suitably pivoted serves to hold it at any desired angle at which it may be set. Near the rear of the head is journaled an upright shaft 13 having a pulley 14 driven by a belt 15 connected to a suitable source of power. An eccentric 16, affixed to the shaft 13, actuates a lever 17 whose forward end has a suitable bearing upon a portion of the head. A swiveled block or cross-head 18, carried by the lever 17 and which is adapted to reciprocate in a slot 19 formed in the head, serves as a movable pivot upon which the lever is fulcrumed. 20 is the trimming-knife, affixed in any suitable manner to the forward end of the lever 17. By reason of the construction by which the lever 17 is mounted, rotation of the shaft 13 causes the knife 20 to describe an elliptical motion, of which a development is shown by dotted lines in Fig. 5.

It will be noticed that the knife, in addition to being beveled at 21, in the same man-

ner as a chisel, is beveled at each side edge 22, thereby causing the knife to cut in three directions.

Work-rest support.—The support for the work-rest, against which the shoe *a* is adapted to be held during the operation, is indicated at 25, under the knife 20. The said support has vertical dovetails 26 which occupy dovetailed guides 27 formed on a horizontally movable carriage 30. The carriage 30 is movably supported on the head 10 by dovetailed guides 31 formed thereon, and is normally held toward the front of the head by a spring 32.

Channeling-knife.—28 is a screw-threaded post carried by the work-rest support and adjustably held therein by a thumb-nut 29. The post 28 is provided with a spline or key 49 which prevents it from turning in the rest 25, and with rollers 33 upon which the shoe *a* is adapted to roll as it advances during the operation hereinafter described. The upper end of the post is also provided with a rigid clamp 34, in which is secured 25 a stationary channel-knife 35, directly beneath and close to the rounding-knife 20. The post and thereby the upper work-rest or roll 33 and the channeling knife are adjusted by rotating the nut 29 and are vertically movable in a manner hereinafter described.

Feeding mechanisms.—The work-feeding mechanism comprises two feeding jaws of which the forward jaw 40 is rigidly secured to the forward end of an eccentric lever 37, mounted above and parallel to the eccentric lever 17. The lower edge of said jaw extends slightly below the rounding knife and is adapted to engage the welt or extension *b* of the sole *b*. This edge, however, is cut away in the center to permit the edge 21 of the rounding knife to project therethrough in penetrating the sole. The jaw therefore acts as a cutting-block to resist the pressure of the knife without coming into contact therewith. The rear feeding-jaw, indicated at 41, is formed at its upper end to straddle the eccentric lever 37 to which it is pivoted by a stud 42. The rear 40 end of the lever 37 embraces and is actuated by an eccentric 43 affixed to a vertical stud-shaft 44 mounted in bearings in the head 10. Rotation is imparted to the shaft 44 by the shaft 13 through spur-gears 45 45, which, 50 rotating in opposite directions, cause the levers 17 and 37 to move oppositely from front to rear, but together from side to side, as hereinafter explained.

38 is an adjustable cross-bar, providing a 60 fulcrum for the lever 37 and supported upon suitable projections forming part of the head 10. Said cross-bar has formed in its ends slots 39 which are occupied by bolts 46. The bolts are screw-threaded into said supporting projections, and serve to clamp the

cross-bar 38 thereto at any desired position within the range of the slots 39. A block 47 swiveled upon the cross-bar occupies a longitudinal slot 48 formed approximately midway between the ends of the lever 37. 70 By reason of this construction, the lever 37 is permitted to move bodily relatively to its fulcrum, hence the feeding jaws receive an elliptical or approximately circular motion, as far as the lever 37 is concerned. Adjustment of the cross-bar 38 and consequently that of the fulcrum or block 47 relatively to the lever 37 produces more or less lateral feeding motion of the jaws 40 and 41.

As previously stated, the levers 17 and 37 80 move longitudinally in opposite directions, and it will now be explained how the jaws 40 and 41 are opened and closed thereby, although both jaws are carried by the lever 37.

At a suitable point between the ends of the rear jaw 41 are pivotally connected the forwardly-extending reaches 50 of a sliding member 51, which loosely straddles and rests upon the lever 17. The said reaches extend along the sides of the lever 17 and are connected at their rear ends by a bridge 52 having bearing upon the lever. A spring 53 connected to the lever and the bridge 52 serves to hold the member 51 normally forward. The member 51 therefore yieldingly presses the rear jaw 41 toward the jaw 40. An overhanging member 54 on the lever 17 prevents the rear end of the member 51 from rising, but allows it limited free lateral movement in any direction for a purpose 95 hereinafter explained.

The rounding-knife mechanism and the feeding-jaw mechanism having been described individually, I will now explain 105 their combined operation before going into further detail of the machine.

Operation.—Referring to Fig. 6, it will be seen that the jaws are open and the rounding-knife in its rearward position. This may be considered the starting position of the machine, the starting and stopping of which may be controlled in any suitable manner, (not shown), such as by a treadle-operated clutch-pulley for driving the belt 15. In this position, the forward position of the member 51 is limited by stops 55 on the lever 17. As previously stated, the free lateral movement of the member 51 is limited, the forward movement, as just stated, by the stops 55, the rearward movement by the member 54, and the sidewise movement by the reaches 50 overhanging the side edges of the lever 17. Rotation of the shafts 13 and 44 in opposite directions, as indicated by the arrows in Figs. 3, 4, and 5, causes the levers 17 and 37 to move forwardly and backwardly respectively, and both toward the right of the machine. The lever 17 moving forwardly, carries with it the rounding- 110 115 120 125 130

knife 20, the member 51, and the lower end of the rear feeding jaw 41, which it may be here stated, is bifurcated in order that it may straddle the trimming-knife, as shown, and not interfere with the movement thereof. The lever 37 in moving backwardly carries with it the forward feeding-jaw 40 and the upper end of the jaw 41. The lower ends of the jaws are thus moved toward each other, the rear jaw, as previously described, being held by spring tension. The forward and backward motion of the member 51 is produced by that of the lever 17, but inasmuch as the sidewise motion of said member is produced by the lever 37, the relative motions of the lever 17 and the member 51 vary both in length and speed. The variation in movement just described is made possible by the aforesaid limited free lateral movement in any direction of the member 51. It may be here stated that the forward and backward motion of the rounding-knife is greater than the sidewise motion thereof, but that the sidewise motion of the feeding-jaws is greater than the forward and backward motion thereof. This is for the purpose of giving the rounding-knife a maximum chisel-like motion, and for giving the jaws a maximum feeding motion.

30 A shoe *a* having a sole *b* to be rounded and channeled is presented to the machine, as shown in Fig. 1, although the parts of the machine should be in the position shown by Fig. 6. While the rounding knife is penetrating the extension *b'* of the sole *b*, the feeding jaws clamp the extension. The initial stress of the rounding knife is sustained by the gage 56, but the jaw 40 in moving to the rear takes such stress from the gage and thereafter feeds the work in conjunction with the jaw 41. The jaw 40 engages the extension before the forward end of the knife emerges from the forward side of the sole extension. The rounding knife moves laterally while the jaws are feeding the work; but inasmuch as the lateral movement of the jaws exceeds that of the knife, the work is caused to gain on the knife, causing one of the longitudinal edges 22 of the knife to elongate the cut. The longitudinal movement of the knife continues during the feeding operation, and a drawing cut is thus performed by the longitudinal edge of the knife. As the work is advanced on the rollers 33, the channeling knife 35 enters the sole *b* at a suitable distance from the incision made by the rounding-knife. 180 degrees' continued rotation of the shaft 13, or the remaining 90 degrees of the first revolution, and the first 90 degrees of the next revolution cause the rounding-knife to recede from the work and move to the right for the next incision. In receding, the stops 55 on the lever 17 engage the bridge 52 of the member 51, thus causing the rear jaw to be disengaged from the sole. The lever 37 at the same time disengages the forward jaw from the work and moves both jaws to the right, with the rounding-knife for a fresh grip upon the work. The shoe is, of course, held 70 and guided in the usual manner by the operator, so that between the unclamping and clamping of the feeding-jaws, the shoe is manually held stationary.

75 *Gage mechanism.*—The means for gaging the work so as to leave more or less extension to the sole comprises a movable work-gage 56 mounted in vertical guides 57 on the head. The lower edge of said gage is adapted to set into the angle formed by the seam of the upper and the welt, but is so formed that it cannot enter the crease and become wedged between the upper and welt. As shown by Fig. 1, one surface of the gage bears against the extension of the outer sole, 80 and the other work-engaging surface is substantially at right angles to the extension of the sole and presses the upper against the edge surface of the insole. The section of the shoe as shown by Fig. 1 is 85 taken at the ball portion where the upper extends away from the outer sole at a right angle; but at other points where the upper and sole extension converge at an acute angle, such as at the shank, the gage is prevented 90 from entering the crease of the inseam by its convex surface which lies against the shoe upper. As a result of this convex formation of the gage, the point of contact between the upper and the contiguous 95 surface of the gage moves away from the sole extension as the angle of the upper and sole extension grows more acute. The gage will not, therefore, enter the crease of the inseam at any part of the shoe. The 100 shoe being held against the gage 56 as it progresses, is given an extension of greater or less width, according to the distance at which the lower edge of the gage sets below the rounding-knife.

105 A rack 58 of gear teeth is formed on the upper end of the gage, and is engaged by a gear-segment 59 affixed to a shaft 60 extending through the upper portion of the head 110 10. One end of said shaft projects through a bracket 61 forming a part of the head and has on its projecting end a bell-crank lever 62 affixed thereto. The arm 63 of said lever is pivoted to a rod 64 which is adapted to be moved vertically by a treadle (not shown). 115 Upward movement of the rod 64, by reason of this construction, lowers the gage 56, thus moving the shoe farther below the rounding-knife, and leaving a wider extension *b'* to the sole *b*. This can be accomplished 120 while the machine is in operation to produce an extension of varied width, as the style of some shoes demands. The movement of the work-gage is limited by thumb-screws 65 65 threaded into the bracket 61 and adapted to 130

be engaged by an ear 66 on the arm 63. A spring 67 on the shaft 60 normally holds the gage in a raised position.

The arm 68 of the bell-crank lever 62 is connected by a pivoted link 69 to a lever 70 affixed to one end of a shaft 71 extending through the carriage 30. A gear-segment 72 affixed to the shaft 71 within the carriage intermeshes with a rack 73 formed on the rear face of the dovetailed portion 26 of the work-rest 25. It is therefore evident that, by means of these connections, the work-rest and channeling-knife are slightly raised when the work-gage is lowered, and vice-versa. By reason of this construction, in rounding the shank of the sole, where the extension thereof is narrowest, the channel cut by the knife 35 is formed at a considerable distance from the edge cut by the rounding-knife. This increased distance between the edge and the channel, which subsequently receives the stitches for securing the sole, places the stitches out of danger of being encountered by the trimming or finishing cutter which is usually employed to remove the sharp edges of the shank.

For convenience in positioning a shoe to be rounded, the work-rest is provided with means whereby it may be retracted either by hand or treadle. Said means comprises a yoke 74 pivoted at 75 75 to the head 10 and underhanging the carriage 30. Said yoke is provided with slots 76 through which the shaft extends, and a handle 77. Connected to said handle is a chain 78 which extends over an idler 79 and thence to a suitable treadle, not shown. It may therefore be seen that the carriage 30, carrying with it the work-rest, may be retracted by swinging the yoke 74 backwardly upon the pivots 75 75, either by means of the handle 77 or the treadle above mentioned.

The member 51 is provided with a yoke 80 which is adapted to impinge against a buffer 81 of leather or other suitable material on that portion of the head in which the lever 17 is fulcrumed. This occurs, however, only when the machine is being driven without a sole *b* between the jaws 40 41, to prevent the jaws from impinging against each other and thus becoming worn.

Having thus explained the nature of the invention, and described a way of constructing and using the same, although without attempting to set forth all of the forms in which it may be made, or all of the modes of its use, I declare that what I claim is:

1. A machine of the character described, comprising a frame, a work gage, a rounding knife, a carriage slidably mounted on said frame movable toward and from the work gage, a work rest support slidably mounted on said carriage and movable thereon toward and from said rounding knife, means for manually moving said car-

riage, means for manually moving said work rest support, a post on said support and extending thereabove, a roll on said post to engage the face of the shoe sole, a channeling knife supported by said post at the end of the roller, and means for vertically adjusting said post and thereby said channeling knife and said roll.

2. A machine of the character described comprising means for feeding the work step by step, sole-rounding means adapted to incise the work and laterally movable relatively to the work-feeding means, and instrumentalities for causing said sole-rounding means to incise the work during the feeding thereof by a lateral movement independent of the lateral movement of the work-feeding means but in the same direction of movement.

3. A machine of the character described comprising means for feeding the work step by step, a rounding knife having a continuous cutting edge adapted to penetrate the work, and means for causing said rounding knife to penetrate and move in the same direction as the work during the feeding thereof, but at a slower rate of speed than the work.

4. In a machine of the character described, a work gage, laterally movable jaws for feeding the work, a laterally movable rounding knife having cutting end and side edges, and instrumentalities for imparting independent intermittent lateral movements to said knife and jaws to incise the work as it is being fed.

5. In a machine of the character described, a work gage, a work rest, a knife movable toward and from and laterally with respect to the work rest, said knife having end and side cutting edges, means for feeding the work and means for imparting the described movement to the knife.

6. In a machine of the character described, a work gage, a work rest, a knife movable toward and from and laterally with respect to the work rest, jaws for feeding the work, means for laterally feeding said jaws, and means for imparting said described movement to said knife to cause it to move simultaneously with the jaws in the same direction.

7. A machine of the character described, comprising a rounding knife, means for reciprocating said knife across and also longitudinally of the feed, a normally stationary gage for engaging the welt of the shoe, a work rest against which the face of the sole may be engaged, and means for feeding the shoe comprising co-acting jaws one engaging the welt and the other the sole, a vibratory support for said jaws and means for actuating said jaws to clamp the work and vibrating said support to feed the work.

8. A machine of the character described, comprising a pair of jaws for intermit-

- tently clamping the work, one of said jaws being movable relatively to the other, and a pair of eccentrics one of which reciprocates the jaws in unison to feed the work, and both of which open and close the jaws.
- 5 9. A machine of the character described, comprising a pair of eccentrics, and a pair of jaws of which one is movable relatively to the other, a vibratory support for said jaws, so arranged as to be vibrated by one of said eccentrics to cause the jaws to feed the work, and means adapted to be reciprocated by the other eccentric to close the movable jaw.
- 10 10. A machine of the character described, comprising a rounding knife, a gage adapted to engage the work between the welt and the upper, a sole support to engage the outer face or side of the sole, co-acting feeding jaws for engaging the welt side and the outer side of the sole, a vibratory support for both jaws, and eccentric mechanism for moving said support and thereby said jaws bodily with relation to the gage and sole support to feed the work, and for opening and closing said jaws.
- 15 11. A machine of the character described, comprising a rounding knife, a movable support for said rounding knife, means for actuating said support, a pair of movable jaws for clamping and feeding the work, a vibratory support for both said jaws, means for vibrating said jaw support to feed the work, and means connecting one of said jaws and said knife support whereby said jaws are closed and opened.
- 20 12. A machine of the character described, comprising a pair of co-acting work-feeding jaws, a supporting member to which one of said jaws is rigidly attached, and to which the other jaw is hinged in juxta-relation to said rigid jaw, means for actuating said jaw-supporting member to impart to said jaws an approximately circular bodily movement, and means for causing said hinged jaw to swing toward and from said rigid jaw to clamp the work.
- 25 13. A machine of the character described, comprising a rounding knife, a member for supporting said knife, means for actuating said member to cause the knife to operate upon the work, a pair of co-acting jaws adapted to clamp between them the work, an oscillatory member for supporting both said jaws, means for actuating said jaw-supporting member to feed the work, and means actuated by said knife-supporting member for closing and opening said jaws to clamp the work.
- 30 14. A machine of the character described comprising a movable support, a pair of co-operative feeding members mounted upon said support, means for moving said support to cause said feeding members to describe an endless path of movement, and means for moving one of said feeding members toward and from the other to clamp and release the work.
- 35 15. In a machine of the character described, a rounding knife, a gage arranged to brace the sole extension to the action of said knife, and means arranged to press the sole extension from said gage toward said knife while the knife is passing through said extension, said means and knife being movable to feed the work.
- 40 16. In a machine of the character described, a rounding knife, a gage arranged to brace the sole extension to the action of said knife, two co-operative clamping members arranged to engage said extension, and means arranged to move said clamping members to clamp said extension and feed the work, one of said clamping members being arranged to take the stress of said rounding knife from said gage.
- 45 17. A machine of the character described, comprising a rounding knife, a channeling knife, a carriage for the channeling knife movable toward and from the rounding knife, a normally stationary gage adapted to engage the work throughout its length to position it with relation to the two knives, a rack on said gage, a rack on said carriage, toothed segments for engaging said racks, and operative connections between said segments, whereby when one is rocked the other will be rocked likewise with the result that the gage and the channeling knife will be adjusted simultaneously with respect to the rounding knife.
- 50 18. A machine of the character described, comprising a rounding knife operating in a fixed plane, a work rest movable with relation to said rounding knife, a channeling knife mounted upon said work rest, a single movable gage adapted to engage the work to position it with relation to said rounding knife and said channeling knife, means whereby said gage may be manually moved with relation to said rounding knife and said channeling knife, means controlled and actuated by said gage-moving means for moving said work rest with relation to said rounding knife, whereby when the extension of the sole is reduced in width the channel is formed at a relatively greater distance from the edge thereof, and means for independently adjusting said channeling knife relatively to said gage and rounding knife.
- 55 19. A combined sole-rounding and channeling machine comprising a rounding knife, means for actuating said knife, a channeling knife, an inseam gage in the line of the rounding knife, said gage being arranged to be engaged continuously by the work, and to vary the width of the sole extension, and manually operative means for relatively adjusting said gage and said

- knives whereby when the extension on the sole is reduced in width as along the shank, the channel is formed at a relatively greater distance from the edge of the extension.
- 5 20. In a machine of the character described, a rounding knife, a channeling knife, a work gage arranged to engage the work throughout its length, and means for simultaneously adjusting said channeling 10 knife and work gage with respect to the rounding knife so that, when the extension of the sole is reduced in width, the channel is formed at a greater distance from the edge thereof, said means comprising a positive 15 connection between said gage and said channeling knife.
21. A machine of the character described, having in combination a trimming knife, means engaging opposite faces of the sole for feeding a shoe, an adjustable gage to 20 guide and adjust the shoe with the part to be trimmed in position to be acted upon by the knife, and means for vibrating the knife during the feeding action of said feeding 25 means, said vibrating of the knife being transverse to the line of feed and in the direction of feed.
22. A machine of the character described, comprising work-feeding means, a flat 30 rounding knife, means for vibrating the knife during the feeding action of said feeding means to cause the knife to move transversely to the line of feed and to change its angle with relation to the work, and a cutting abutment movable with the knife in the line of the feed.
23. A machine of the character set forth comprising a work-guide and a sole-support both fixed against movement in the direction 40 of feed, in combination with a trimming knife, means for moving said knife both transversely and longitudinally of the direction of feed, a clamp feeding mechanism comprising a vibratory support and coactive 45 feeding members thereon of which one is movable toward the other, and eccentric mechanism for effecting the opening and closing of said jaws and their movement in the direction of feed to feed the work.
- 50 24. In a machine of the character set forth, a main frame, a work guide, feeding mechanism, a rounding knife, a spring-pressed carriage mounted to slide in a guideway on the main frame and movable back 55 and forth relatively to the work gage but fixed in the direction of feed, a slide mounted in guideways in said carriage to move up and down toward and from the rounding knife, a channeling knife on said slide, 60 means for independently adjusting said channeling knife on said slide toward and from said rounding knife, manually operated means for moving said carriage and slide backwardly from said work gage, and manu-
- ally operated means for moving said slide 65 downwardly away from said knife.
25. In a machine of the character set forth, a work guide, work-feeding mechanism, comprising a pivoted member, a jaw on said member, means for oscillating said member about its pivot to move said jaw longitudinally of the direction of feed, and a second jaw supported by said member and movable toward and from the first-mentioned jaw to clamp the work and also move 70 with said jaw to feed the work, in combination with a rounding knife, a knife carrier, means for actuating said knife carrier, and a connection between said knife carrier and said second-mentioned jaw whereby said jaw 75 is caused to co-operate with the first-mentioned jaw.
26. In a machine of the character described, a rounding knife, a work guide, and work-feeding mechanism comprising opposing 80 clamping jaws, a pivoted lever, one of said jaws being rigidly secured to said lever and the other being pivoted thereto, and eccentric mechanism for oscillating said lever about its pivot and actuating said pivoted 85 jaw.
27. In a machine of the character described, a rounding knife, a gage arranged to brace the sole extension against the stress of said knife, and movable means arranged 90 to intermittently engage the sole extension to take said stress from said gage and to feed the work.
28. A machine of the character described comprising a rounding knife, a gage arranged to act upon the sole extension and upper, a feeding member arranged to engage the tread surface of the sole, means for causing said feeding member to act against the sole to press the extension thereof 100 against said gage, and a feeding member arranged to engage the sole extension to co-operate with the first-named feeding member to clamp said extension, said feeding members being movable laterally to feed. 105
29. In a machine of the character described, a longitudinally and laterally movable rounding knife, a gage arranged to brace the sole extension against the stress of said knife, a member arranged to engage 110 the sole extension adjacent said knife, and means arranged to cause said member to traverse an endless curvilinear path to take the stress of said knife from said gage and feed the work.
30. In a machine of the character described, two coacting clamping members arranged to clamp the work, means forming a hinge connection between said members, and means arranged to cause said members to 115 traverse endless curvilinear paths to clamp 120 and feed the work.
31. In a machine of the character de-

scribed, two coacting clamping members arranged to clamp the work, means forming a hinge connection between said members, and means arranged to cause one of said members to traverse an elliptic path and to cause the other one of said members to traverse an endless path, to clamp and feed the work.

32. A machine of the character described comprising coöperative members movable toward each other to clamp the sole extension and movable laterally to feed the shoe, a rounding knife arranged to move substantially at right angles to the plane of the sole to cut and to move laterally with said clamping members, and means for operating said clamping members and knife to give the clamping members more feeding movement than clamping movement and to give said knife more endwise cutting movement than lateral movement.

33. A machine of the character described comprising coöperative members movable toward each other to clamp the sole extension and movable laterally to feed the shoe,

a rounding knife arranged to move substantially at right angles to the plane of the sole to cut and to move laterally with said clamping members, and means for causing lateral movement of said clamping members and lateral movement of said knife while the latter is in the work, said means being arranged to cause said lateral movements to be unequal.

34. In a machine of the character described, a rounding knife having a longitudinal cutting edge, means arranged to reciprocate said knife longitudinally, and means arranged to feed the work relatively to said knife while said knife is moving endwise, to cause said longitudinal edge to perform a drawing cutting action.

In testimony whereof I have affixed my signature, in presence of two witnesses.

HARRIE A. BALLARD.
